UNITED STATES PATENT OFFICE.

JOSEPH HANAUER, OF SPOKANE FALLS, WASHINGTON.

MAIL-BAG.

SPECIFICATION forming part of Letters Patent No. 459,631, dated September 15, 1891.

Application filed August 19, 1891. Serial No. 403,093. (No model.)

To all whom it may concern:

Be it known that I, JOSEPH HANAUER, of Spokane Falls, in the county of Spokane and State of Washington, have invented certain new and useful Improvements in Mail-Bags, of which the following is a specification, reference being had to the accompanying drawings, and to the letters of reference marked thereon.

10 The object of my invention is to improve the fastening devices for mail-bags, whereby the bag is rendered dust and water proof; and it consists in the several details of construction and arrangement of parts hereinabove fully set forth.

15 In the drawings, Figure 1 is a side elevation of a portion of a closed mail-bag embodying my invention. Fig. 2 is a plan showing the bag open. Fig. 3 is a section on the line 20 xx of Fig. 1. Fig. 4 is a similar section illustrating a modification. Fig. 5 is a horizontal section of a portion of the frame. Figs. 6 and 7 show details of the locking device.

Similar letters of reference indicate similar 25 parts in the several figures.

A represents the leather bag.

20 B, B', B², and B³ are side plates hinged together at b, b', b², and b³ to form, when the bag is open, a quadrangular frame, to which 30 the open end or mouth of the bag is attached by rivets a or other suitable fastening devices. When the bag is closed, the plates B and B³ and B' and B², respectively, will form two straight sides. The plates B and B² are somewhat longer than those B' and B³, whereby 35 when the bag is closed the joints at the hinges b and b² will not be opposite each other, and consequently the frame will not be materially weakened or more liable to bend at these 40 points. The plates B and B² are provided with top plates or flanges C and C', adapted when the bag is closed to overlap the top edges of the side plates B' and B³ and to form a close joint therewith. The several 45 hinges are riveted to the side plates, the two end hinges b' and b³ having preferably top flanges a' a' overlapping the top surface of the side plates to give additional strength. The hinge b has no top flange; but the hinge 50 b² has a flange C², which when the bag is

closed extends across the top surface of the plates and overlaps the top edge of the hinge b.

D is a pin which passes through the flange C² and also through a lug E, projecting inwardly from the hinge b², as shown in Fig. 6. 55 The flange C² and lug E form bearings for the pin D, in which it is adapted to turn. At its upper end the pin is provided with a suitable thumb-piece D' and at its lower end, below the lug E, with a hook F. Between the under 60 surface of the flange C² and the upper surface of the lug E a coiled spring G surrounds the pin D, one end of the spring being fastened to the pin and the other end to either the lug or the flange. The outer surface of the hook 65 is rounded or beveled, as shown at f. To the inner surface of the hinge b a hook H is rigidly attached, with which the hook F is adapted to interlock when the bag is closed. The outer surface of the hook H is also beveled at h, as shown in Fig. 5. The normal 70 tendency of the spring G is to keep the two hooks in engagement when the bag is closed, and the beveled outer surfaces of the two hooks permit them to automatically engage 75 each other when pressure is applied to force the side plates together. When it is desired to open the bag, pressure applied to the thumb-piece D' will cause the pin D to turn against the force of the spring G and swing 80 the hook F out of engagement with the hook H.

J is a staple rigidly secured to the flange C² and extending over the thumb-piece D'. The staple J and thumb-piece D' are so arranged 85 relatively to each other that the thumb-piece when in its normal position will extend obliquely across the open space between the two posts of the staple, as shown in Figs. 2 and 7. The pin D, to which the thumb-piece D' is attached, is located close to and inside one of 90 the posts of the staple, and a space is left between the other post and the thumb-piece sufficient to enable the link k of the padlock K to be inserted. When the link k is in position, it serves to prevent movement of the 95 thumb-piece D', and consequently the bag cannot be opened.

L represents a tag-holder secured to one of the flanges C C', and which may be of any approved construction.

I will now describe the manner of forming the side plates, which constitutes one of the most essential features of my invention. Each side plate consists of an interior strip 5 of metal m and an outer covering of vulcanized rubber m' . In the case of the flanged side plates a strip of metal is employed both for the plate and its flange, as clearly shown in Figs. 3 and 4. Preferably for this purpose one strip of metal bent lengthwise at right angles is used; but it is obvious that two separate strips of metal might be used with good results. I also prefer to corrugate the metal lengthwise, as shown in Fig. 3, as 15 the strip may thus be thinner and still possess the necessary strength. In Fig. 4 I have shown the metal strips not corrugated, and I do not limit myself specially to the use of either construction, as both may be used with 20 good results.

Many advantages arise from the use of a frame constructed in accordance with my invention. The metal strips incased in rubber will give the frame when closed a certain degree of elasticity and yet make the sides sufficiently rigid to withstand any ordinary attempt to force the sack open. The overlapping flanges $C C'$ and the top edges of the plates overlapped will also yield to a certain 25 degree on account of the elasticity of the rubber, and a very close joint can therefore be formed between them. The locking device is also simple, inexpensive, and secure and may be easily and quickly operated.

35 Having described my invention, I claim—
1. In a mail-bag, a frame attached to the mouth of the bag and consisting of a series of side plates hinged together, each plate composed of a strip of metal inclosed in vulcanized rubber, substantially as described.

40 2. In a mail-bag, a frame attached to the mouth of the bag and consisting of a series of side plates hinged together, each plate

composed of a strip of corrugated metal inclosed in vulcanized rubber, substantially as 45 described.

3. In a mail-bag, a frame attached to the mouth of the bag and consisting of four side plates hinged together, two of said plates having top flanges adapted to overlap the top 50 edges of the other two plates, each side plate and flange being composed of a strip of metal inclosed in vulcanized rubber, substantially as described.

4. In a mail-bag, a frame attached to the 55 mouth of the bag and consisting of side plates hinged together, combined with a locking device consisting of a rotating hook mounted on one side, a fixed hook on the opposite side, the two hooks being located within the bag 60 and adapted to interlock when the bag is closed, and a spring to hold the hooks in engagement, substantially as described.

5. In a mail-bag, a frame attached to the mouth of the bag and consisting of side plates 65 hinged together, combined with a locking device consisting of a hook carried by a pin rotating in bearings on one of the sides, a fixed hook on the opposite side, the two hooks being located within the bag and adapted to 70 interlock when the bag is closed, a spring to hold the hooks in engagement, a thumb-piece at the upper end of the rotating pin outside the bag, a staple rigidly secured to the side and extending over the thumb-piece obliquely 75 thereto, and a device inserted between the thumb-piece and one post of the staple to prevent turning of the rotating pin, substantially as described.

In testimony whereof I have hereunto set 80 my hand and seal.

JOSEPH HANAUER. [L. S.]
